UNITED STATES PATENT OFFICE.

ARTHUR MIDDLETON ROSE, OF YONKERS, NEW YORK, ASSIGNOR TO MATTHEW J. WHITTALL, OF WORCESTER, MASSACHUSETTS.

DESIGN FOR CARPET.

SPECIFICATION forming part of Design No. 24,028, dated February 12, 1895.

Application filed January 16, 1895. Serial No. 535,160. Term of patent 3½ years.

Be it known that I, ARTHUR MIDDLETON ROSE, residing at Yonkers, county of Westchester, State of New York, have invented and produced a new and original Design for a Pattern to be Wrought into Wilton and other Carpetings in such coloring as may be designed; and I do hereby declare that the drawing accompanying this specification gives and conveys to any one skilled in the art of carpet weaving and manufacture a clear understanding of the same, and is sufficient to enable such person to use my invention.

The design consists of the body A and a border B.

The body A is decorated with a series of ornamental figures after Persian style, the principal figure appearing at intervals in the center of a conventionalized leaf. The border B is decorated with similar ornaments to the body, the principal leaf figure being near 20 the outer edge.

What I claim as my invention, and desire to secure by Letters Patent, is—

1. In a design for a carpet, the body A, substantially as shown.

2. In a design for a carpet, the border B, substantially as shown.

3. The design for carpets, consisting of the body A, and the border B, substantially as shown.

ARTHUR MIDDLETON ROSE.
